UNITED STATES PATENT OFFICE.

WILLIAM MEERBOTT, JR., OF JERSEY CITY, NEW JERSEY.

INTERCHANGEABLE-INITIAL RING.

SPECIFICATION forming part of Letters Patent No. 363,076, dated May 17, 1887.

Application filed September 21, 1886. Serial No. 214,108. (No model.)

To all whom it may concern:

Be it known that I, WILLIAM MEERBOTT, Jr., of Jersey City, in the county of Hudson and State of New Jersey, have invented certain new and useful Improvements in Interchangeable-Initial Rings, of which the following is a specification.

This invention relates to that class of rings provided with initials, monogram letters, or ornaments of stone held on stones in the ring, said initials, monograms, or stones being interchangeable—that is, adapted to be removed from one ring and placed in another.

The object of my invention is to provide rings with interchangeable initials, and to facilitate the interchanging of the initials and also of the stone.

In the accompanying drawings, Figure 1 is a face view of my interchangeable-initial ring. Fig. 2 is a horizontal section of the same on the line $y-y$, Fig. 3; Fig. 3, a cross-sectional view of the same on the line $x-x$, Fig. 2. Fig. 4 is a cross-sectional view on the line $z-z$, Fig. 3, parts being broken out and others shown in section in dotted lines.

Similar letters of reference indicate corresponding parts.

The ring A is provided with a recess or cavity, B, for receiving the stone C. Behind the bottom of the recess or cavity B the groove D is formed, extending the length of the said cavity—that is, parallel to the axis of the ring. In a plate, E, forming the bottom of back of the cavity B, two or more apertures, F, are provided, which are in direct communication with the groove D. The stone C is provided with as many apertures, G, as there are apertures in the back or bottom of the recess or cavity.

The monogram, initial, or ornament H, which may be made of gold, silver, or other precious metal, is provided with as many pins, J, on its back as there are apertures in the back of the cavity, said pins being provided at their free ends with notches K in one or both sides, said pins being of such length as to pass entirely through the stone and through the apertures in the back of the cavity B into the groove D. A sliding key, M, fitting quite snugly in the groove D is forked or provided with two prongs, the distance between the inner edges of which is about equal to the thickness of the diameter of the pins J at the nuts K. The key M is

provided at its closed end with an aperture, N, for inserting a hook or other suitable implement, and the ring is provided with a notch, O, by which the hook can be passed into the aperture O.

The stone is placed into the cavity B and the initial H, monogram, or other ornament is placed upon the face of the stone, the pins J passing through the same and the back of the cavity into the groove D. The sliding key M is then inserted through the aperture in the top edge of the frame for holding the stone and into the groove D, the inner edges of the 65 prongs of the key M facing the pin J and thus holding it, which in turn holds the stone. When it is desired to remove the initial from the stone, the said key is removed.

Any initial, monogram, or ornament can thus be fastened on any stone and held in any ring adapted for the purpose, thus facilitating the interchanging of stones, initials, or monograms.

I have shown in the drawings a stone with a curved surface; but stones made with flat faces may be used. In place of the single key, two or more keys may be provided for holding one or more initial letters. In place of stones, enameled plates, glass, composition, or other material can be placed into the cavity B, and, if desired, may be permanently secured in the same, the initials only being removable and being fastened in the manner described.

Having thus described my invention, I claim as new and desire to secure by Letters Patent—

1. The combination, with a ring, of a detachable initial or ornament having pins adapted to be passed into the ring, and a key which can be passed into the ring and engage said pins, substantially as shown and described.

2. The combination, with a ring, of a detachable initial having pins, said pins having notches at the ends, and of a key adapted to be passed through an aperture in the ring to engage the pins of the initial, substantially as shown and described.

3. The combination, with a ring, of a detachable stone having apertures, a detachable initial or ornament provided with pins, and a key for engaging said pins, substantially as shown and described.

4. The combination, with a ring having a

cavity for receiving a stone, apertures in the bottom of said cavity, and a groove or recess behind the cavity, of a stone in the cavity having apertures, an initial or ornament having pins, and a key fitting in the above-mentioned groove for engagement with the said pins, substantially as shown and described.

5. The combination, with a ring having a cavity for receiving a stone, apertures being provided in the bottom of the cavity and a groove behind the apertures, of a stone provided with apertures, an initial or ornament provided with pins, and a forked key provided at the closed end with an aperture, substantially as shown and described.

10. The combination of a ring having a cavity for receiving a stone, a stone in the cavity

provided with apertures, an initial or ornament provided with pins, and a sliding key passed into the said stone, substantially as shown and described.

15. The combination, with a ring, of a detachable initial having pins on the same, and a forked and sliding key for engagement with the initials, substantially as shown and described.

20. In testimony that I claim the foregoing as my invention I have signed my name in presence of two subscribing witnesses.

25. WILLIAM MEERBOTT, JR.
